ENGINE

André J. Meyer, Lexington, Ky., assignor to
 Mawen Motor Corporation, New York, N. Y.,
 a corporation of Delaware

Application June 7, 1938, Serial No. 212,222

21 Claims. (CL 123—44)

The present invention relates to internal combustion engines and has particular reference to radial cylinder engines of the kind in which flow of gases either to or from the cylinder, or both, is controlled by ports arranged in an annular valve member encircling the cylinder bank and between which and the bank there is relative rotary movement.

In engines of this kind both the valve member and the cylinder bank may rotate, but at different speeds, around a stationary crankshaft, or the valve member may be stationary with the cylinder bank and crankshaft rotating but at different speeds. In the type in which both cylinder bank and crankshaft rotate, they may rotate either in the same or opposite directions. For numerous reasons not germane to the present invention, the type in which the valve member is stationary and the cylinders and crankshaft turn in opposed directions is ordinarily to be preferred and the present invention will be described in its application to this particular type. For convenience it will be referred to as a bi-rotary engine, the term bi-rotary, however, being understood to be generic to all types of engines of the kind in which there is relative rotation between a cylinder bank and an encircling annular valve member.

In the bi-rotary engine as well as in other types, the efficiency of the engine and the power capacity depend among other things upon the efficiency with which spent combustion gases are scavenged from the engine cylinders and replaced with charges of fresh combustion gases. From the standpoint of volumetric efficiency, the bi-rotary engine is superior to many other types of engines, largely because of the comparatively large and free port areas through which it is possible to introduce and exhaust gases from the cylinders. The nature of the porting which permits this relatively free flow of gases to and from the cylinders introduces however, certain special factors influencing the gas flow which are not present in other types of engines.

The general object of the present invention is to provide for improved gas flow, particularly to the cylinders of engines of the kind under discussion, through the provision of improved valve porting, particularly inlet valve porting. The manner in which the above general object and other and more detailed objects of the invention may be attained and the advantages to be derived from utilization of structure embodying the invention will best be understood from a consideration of the ensuing portion of this specifi-

cation descriptive of apparatus embodying the invention, taken in conjunction with the accompanying drawings in which:

Fig. 1 is a fragmentary sectional longitudinal section showing part of an engine embodying the invention;

Fig. 2 is an elevation looking from the right of Fig. 1, part of the figure being sectioned on the central plane of rotation of the cylinder bank;

Fig. 3 is a view on enlarged scale, partly in elevation and partly in section, of a ported portion of the annular valve member showing the relation between the valve ports and a cylinder port;

Fig. 4 is a section taken on the line 4—4 of Fig. 3;

Figs. 5 to 10, inclusive, are sections taken along the radial lines numbered respectively 5 to 10 in Fig. 4;

Figs. 11 to 14 are sections taken on the respectively numbered section lines of Fig. 5; and

Fig. 15 is a view from below of the inlet port shown in Fig. 3.

Referring now more particularly to Figs. 1 and 2, the engine illustrated comprises a single bank of radially arranged cylinders 10. Seven cylinders have been shown in this embodiment but it will be understood that the number of cylinders per bank may be varied and also that engines embodying the invention may be constructed with a plurality of cylinder banks.

Cylinders 10 are secured at their inner ends to a crank case structure indicated generally at 12 and advantageously constructed of two crank case parts or halves bolted together as indicated in Fig. 1. The crank case structure is rotatably mounted on bearings 14 and 16 to revolve about a crankshaft 18 having a crank pin 20 and mounted for rotation in a stationary structure indicated generally at 22. One of the crankshaft bearings is indicated at 24 and the other at 26.

In the embodiment illustrated, one of the pistons 28 is connected by means of a master connecting rod 30 to the crank pin 20 and the remaining pistons of the bank are connected by means of rods 32 pivoted at their inner ends to the inner end of the master rod 30, in known manner. In so far as the present invention is concerned, other known forms of connection between pistons and crank pin may be employed.

The cylinders and crankshaft in the illustrated embodiment both rotate with respect to the stationary structure 22 and further rotate in opposite directions. The desired rotation of these components of the engine is obtained in the

present instance through the medium of gearing comprising a crankshaft gear 34 meshing with a gear 36 fixed on shaft 38 journaled at 40 and 42 in the stationary mounting structure. Shaft 40 in the present instance constitutes the power take-off shaft. Fixed on shaft 38 is a second gear 44 meshing with an idler gear 46 located behind the plane of Fig. 1 and also carried by the stationary mounting structure. Idler 46 meshes with gear 48 which is fixed to the crank case structure of the cylinder bank.

The stationary housing structure 22 includes an annular valve member 50 encircling the ends of the cylinders, this valve member being provided with peripherally spaced inlet and exhaust passages hereinafter to be more fully described. In the engine illustrated, having seven cylinders and arranged for opposite rotation of the cylinder bank and the crankshaft, the number of inlet and exhaust passages required is four each, the inlet passages being indicated generally at 52 and the exhaust passages at 54 in Fig. 2.

The exhaust passages 54 pass substantially directly through the valve member which is advantageously formed with flanged seats 56 around the outer ends of the passages for connection to the valve member of a suitable exhaust manifold (not shown). The inlet passages open outwardly from the side of the valve member where suitable flanged seats 58 are provided for the seating of the ends of the radially extending arms 60 of the inlet manifold which is connected with carbureter 62.

Other manifolding arrangements may be employed within the scope of the present invention, which, as will hereinafter more fully appear, is concerned primarily with the configuration of the valve ports and the portions of the passages in the valve adjacent to the ports.

The valve member 50 is formed with an inner bearing or sealing face 64 which is preferably spherically curved as indicated. The outer ends of the cylinders are open and provide cylindrical bores for the reception of sealing elements 66 which preferably are in the form of annular cuff-like members having sleeve portions mounted for both rotary and axial movement relative to the cylinders and flanged ends having spherically curved sealing surfaces 68 in sliding contact with the sealing surface of the valve member. Sealing rings similar to piston rings are preferably provided between the telescoping parts of the sealing elements and the cylinders and the sealing elements are maintained in sealing contact with the surface of the valve by centrifugal force, preferably aided by springs (not shown) interposed between the ends of the cylinders and the flange portions of the cuffs.

In order to seal the valve ports when they are not in registry with the cylinders, an inner sealing ring indicated generally at 70 is provided. In the embodiment illustrated, this inner sealing ring is made up of a series of segments or shoes 70' each having a central circular opening in which the outer end of the cylinder, and also the sealing cuff with which it is associated, are located. The outer faces of the shoes 70' are also spherically curved to provide sealing surfaces in sliding contact with the inner surface of the valve member.

The several shoes 70' are, like the sealing cuffs, held in sliding contact with the face of the valve member by centrifugal force which may be aided by suitable springs (not shown) interposed

between the shoes and the cylinders and acting to force the shoes in radially outward direction. In so far as the present invention is concerned, the construction of the inner sealing ring may be widely varied and may consist of a single integral ring having a series of openings for the reception of the outer ends of the cylinders and the sealing cuffs.

The general type of engine just described is known and its general mode of operation will be largely evident from the drawings. In the engine illustrated, the cylinder bank rotates in clockwise direction as viewed in Fig. 2 and through the gearing connecting the cylinder bank with the crankshaft the latter is made to rotate in the opposite direction. The engine shown is of the four-cycle type and as will be apparent from Fig. 2, each cylinder will pass in alternation an inlet passage 52 through which gases are drawn into the cylinder on the suction strokes of the pistons and an exhaust passage 54 through which the spent gases are discharged. The desired timing of the engine is effected through choice of suitable gear ratio for the gearing connecting the cylinder bank and the crankshaft, which may readily be computed by known methods which need not be described herein.

In so far as the present invention is concerned, the means by which ignition is effected is not material. The engine may be operated with compression ignition or with ignition effected by any suitable form of ignition means of known character such as high tension electric spark, glow plug, or the like.

As will be evident from Fig. 2, the sealing element 66 associated with each cylinder provides a cylinder port 72 through which fresh charges of combustible gas (or air in case the engine is of the injection type rather than the carbureter type as herein illustrated) and exhaust gases flow. The cylinder port thus constitutes in effect both an inlet passage and an outlet passage.

This port registers with the gas passages in the valve member by passing them in peripheral direction and in accordance with the present invention, improved gas flow to and from the cylinder, particularly to the cylinder, is provided by the special form and configuration of the passages and ports in the valve member as will now be described more particularly with reference to Figs. 3 to 15. In Fig. 3, the direction of relative rotation of the cylinder port 72 with respect to the valve member 50 is in the direction of the arrow 74, and the portion of the cylinder port which is in advance in the direction of this relative movement will for convenience be hereinafter referred to as the leading edge or portion of the port while the portion at the opposite side of the port will be referred to as the trailing edge or portion of the port. Similarly, the edges of the ports in the valve member which are first passed by the cylinder port will be referred to as the leading edges while the portions last passed by the cylinder port to close communication between the ports will be referred to as the trailing edges.

Referring now more particularly to the construction of the inlet passages and ports in the valve member, all of which are of the same configuration so that only one need be described, one characteristic feature of the construction is the formation of the port and passage to produce accelerated flow of the incoming gas, so that at least the first portion of the charge to enter the

cylinder does so at very high velocity. This can to a certain extent be accomplished by narrowing in lateral direction the leading portion of the inlet port opening but the preferred construction 5 provides a web or baffle 76 at the inner end of the inlet passage 52, which web extends transversely of the passage to provide a main inlet port 78 and an auxiliary inlet port 80. As will be seen from Figs. 3 and 5, the auxiliary inlet port is materially smaller in area than the main inlet port and the auxiliary port is in advance of or leads the main port with respect to the sequence of registration with the cylinder port. In the embodiment illustrated, the cylinder port 72 is circular in cross-section and the main inlet port is advantageously formed with its leading and trailing edges, 82 and 84 respectively, curved to the same radius as that of the cylinder port. As will be seen from Fig. 5, these curved edges are 10 curved in opposite directions and inwardly of the port. The leading and trailing edges 86 and 88, respectively, of the auxiliary port 80 are likewise advantageously curved to the same radius as that of the cylinder port but these edges are preferably, as will be seen from Fig. 5, curved in the same direction to provide an arcuate port separated from the main port by the web 76.

As previously noted, the inlet passage 52 is curved laterally to emerge from the side of the 30 valve member and the general configuration of the passage will be clear from the several sections shown in Figs. 4 to 14. The inlet passage 52 in the valve does not necessarily have to emerge from the side of the valve member and its specific 35 configuration may vary widely within the scope of the invention. There are, however, certain characteristics which should be included in the design of the passage if full advantage is to be taken of the principles of the invention. 40 As will be noted from Figs. 3 and 5 to 8, the baffle 76 extends in generally radial direction and the portion 52' of the wall of the inlet passage which lies in front of the baffle is curved in the plane of rotation to deflect the inwardly travelling gases 45 so that they tend to enter the cylinder port in a direction along a chord of the circular orbit of movement of the cylinder port. The orientation of this chord is such that the direction of flow which the walls of the auxiliary inlet passage 50 tend to impart to the inflowing gases may be said to have a radial component and a tangential component in the direction of rotation of the cylinder port relative to the valve member. This direction of flow of the gas when the cylinder port first 55 comes into communication with the leading portion of the valve port is highly desirable whether a baffle is employed or not.

As will be observed from Fig. 15, the exhaust port 90 of the embodiment illustrated also has 60 arcuate leading and trailing edges 92 and 94, respectively, which are curved to the same radius of curvature as the cylinder port, both of these edges being curved in the same direction. Also, the leading and trailing portions 54' and 54'' of 65 the wall of the exhaust passage are advantageously curved in the plane of rotation, as appears more clearly from Fig. 3, so that the outflowing gases are given a direction of flow which has a tangential component in the direction of 70 relative rotation of the valve member with respect to the cylinder bank.

It is to be noted particularly with respect to the leading and trailing edges of the ports in the valve member that the trailing edge 54'' of the 75 exhaust port 54 is curved to register with the

trailing edge of the cylinder port while both the leading and trailing edges of the auxiliary inlet port are curved to register with the leading edge of the cylinder port, and the trailing edge of the main inlet port is curved to register with the 5 trailing edge of the cylinder port. The configuration of the above port edges is more important than the configurations of the leading edges of the exhaust port and the main inlet port.

As will be observed from Fig. 3, the distance 10 between the trailing edge of the exhaust port and the leading edge of the auxiliary inlet port is less than the diameter of the cylinder port so that the cylinder port is temporarily in communication with both inlet and exhaust. In other words, 15 there is overlap of the timing of inlet and exhaust.

With the port arrangement and construction as above described, the action with respect to admission and exhaust of gas to and from the engine cylinder is as follows, commencing with 20 the exhaust portion of the cycle: Before bottom dead center of the piston on the working stroke is reached, the cylinder port comes into communication with the leading edge of the exhaust port, the sealing element or cuff 66 being 25 to the left of the position shown in Fig. 3. As the cylinder port moves relative to the valve member 50 in the direction of the arrow 74 during the ensuing upward exhaust stroke of the piston, full registration between the cylinder and 30 exhaust ports is effected and the area of the exhaust port in communication with the cylinder is thereafter decreased as the cylinder port moves to the position shown in Fig. 3. In order to prevent the pressure of the gases in the cylinder 35 from dropping to the pressure in the exhaust manifold too early in the cycle, which would tend to reduce the velocity of outflow later in the exhaust stroke, the leading portion of the exhaust port may in some instances advantageously 40 be narrowed in lateral direction to somewhat restrict the outflow during the early portion of the exhaust period. During the exhaust period the gases leave the cylinder at high velocity and this high velocity outflow continues in the trailing portion of the cylinder port after the cylinder port comes into communication with the inlet. When the exhaust gases flow at high velocity from the cylinder during the latter part 45 of the exhaust stroke they are capable of producing sub-atmospheric pressure in the cylinder when the piston is near top dead center and this aids in the induction of fresh gas into the cylinder by establishing a pressure differential 50 between the interior of the cylinder and the inlet passage. The higher the velocity of outflow at the end of the exhaust stroke the higher this pressure differential becomes and the desirable condition of high outflow velocity is contributed to by the phase of the present invention which 55 provides the curved trailing wall portion of the exhaust passage, and the curved trailing edge of the exhaust port, which is shaped to register with the trailing portion of the cylinder port. This shaping of these portions of the exhaust port and 60 passage result in substantial elimination of eddy currents, particularly at the important time late in the exhaust stroke when the exhaust port is being closed, and consequently maximum speed 65 of egress of the gases at this time is insured. 70

In the case of an engine which is not supercharged, the pressure differential between the cylinder and the inlet passage at the instant they come into communication provides a means for inducing the flow of fresh gas into the cylinder 75

- and this pressure differential may further be enhanced by delaying opening of the inlet port until appreciably after the piston has passed top dead center and is moving downwardly on the suction stroke. By providing a substantial pressure differential between cylinder and inlet passage when the inlet is first opened and further by shaping the leading portion of the inlet passage so that the velocity of the incoming gases in this portion of the passage may be smoothly accelerated, relatively very high velocity of the initial portion of the incoming charge can be obtained even with an unsupercharged engine. Further, by directing this high velocity initial portion of the incoming charge toward the leading portion of the cylinder port passage, and while the cylinder port is still in communication with the exhaust port, the first portion of the incoming charge may be utilized to aid in scavenging the cylinder of the residual portion of spent combustion gases. By directing the inflowing gases in the manner stated, this scavenging action is obtained with minimum mixing of residual spent gas with the incoming fresh gas.
- In the case of a supercharged engine, the positive pressure produced by the supercharger will, of course, provide ample pressure differential between the inlet passage and the cylinder, but even in the case of a supercharged engine, the direction of flow of the incoming gas into the cylinder port is important in order to avoid mixing of fresh and spent gases in the cylinder and the shaping of the portion of the inlet port which opens first and of the leading portion of the inlet passage is also of importance in securing high velocity admission of the initial portion of the incoming charge, which in effect acts as a scavenging jet for forcing from the cylinder the last of the residual gases.
- The small area of the auxiliary port, which results, among other things in the high initial velocity imparted to the incoming gases, would, if it constituted the sole inlet, adversely affect the volumetric efficiency of the engine but any tendency for the volumetric efficiency of the engine to be reduced by the restricted area of the inlet port is, of course, negated by the ample area of the main inlet port with which the cylinder port comes into registry substantially immediately after registry with the auxiliary port and preferably as soon as the cylinder port has passed out of communication with the exhaust port.
- Because of the fact that the trailing edge of the exhaust port is shaped to register with the trailing edge of the cylinder port, quick closing of this port with minimum wire drawing effect is obtained and the curvature of the leading and trailing wall portions of the exhaust passage 54 serves to minimize turbulence in the outflowing gases, both of these factors contributing to the efficiency with which the cylinder is emptied of the spent gases.
- The curvature of the leading and trailing edges of the auxiliary inlet port so that these edges register with the leading edge of the cylinder port, results in an advantage which will be obvious from the preceding explanation since such curvature not only results in very quick opening of this port, but also serves to direct the incoming gas in a manner which avoids to the greatest extent any intermingling between fresh and spent gas.
- By curving the trailing edge of the main inlet port to register with the trailing edge of the cylinder port, the inlet port is, like the exhaust port,

closed very rapidly and with the minimum of wire drawing, thus contributing to high volumetric efficiency.

It will be evident from the foregoing that with the port arrangements employed in accordance with the principles of the present invention, highly efficient scavenging of the engine cylinders may be effected even in the case of unsupercharged engines. The specific timing of the opening and closing of the ports will vary with different specific engine designs, but by way of example the following may be stated as suitable for the specific port arrangement hereinbefore described, in an engine suitable for automotive use and having a normal maximum operating speed of the crankshaft relative to the cylinder bank of the order of 3,000 R. P. M.:

Inlet opens 10° after top dead center.

Exhaust closes 25° after top dead center.

Intake closes 20° after bottom dead center.

Exhaust opens 45° before bottom dead center.

It will further be evident that in so far as the present invention is concerned, different specific combustion cycles may be employed and the term "gas" as herein employed is to be considered to include any gaseous medium inducted into the cylinders, whether such medium be a combustible gas, or air or other combustion supporting medium to which fuel is added in the cylinder.

With different combustion cycles, certain phases of the present invention will be more important than with other combustion cycles and it is accordingly to be understood that the invention is not limited in its scope to the arrangement shown and described herein by way of example but may be embodied in other specific forms of construction which may employ all of the features of the invention or may utilize some to the exclusion of others. The scope of the invention is to be considered as embracing all forms of structure falling within the purview of the appended claims when they are construed as broadly as the state of the prior art permits.

What I claim is:

1. In a bi-rotary engine, a cylinder bank including a cylinder having a port at its outer end, and an annular valve member having an exhaust gas passage extending therethrough, said passage terminating at its inner end in an exhaust port, said exhaust port being located so as to be brought into and out of communication with the cylinder port by relative rotary movement between the cylinder bank and the valve member, the trailing portion of the wall of said exhaust passage being shaped to direct the outflowing gases after they leave the cylinder port in a direction having a tangential component in the direction of relative movement of the valve member with respect to the cylinder bank.

2. In a bi-rotary engine, a cylinder bank including a cylinder having a port at its outer end, and an annular valve member having an exhaust port located to be brought into and out of communication with the cylinder port by relative rotary movement between the valve member and the cylinder bank, the trailing edge portion of the exhaust port being shaped to substantially register with the trailing edge portion of the cylinder port and the leading edge portion of the exhaust port being shaped to a different contour from that of the leading edge portion of the cylinder port so that said leading edge portions are not in registry as the ports come into com-

munication, whereby to provide less rapid opening of the exhaust ports than closure thereof.

3. In a bi-rotary engine, a cylinder bank including a cylinder having a port at its outer end, and an annular valve member having an exhaust port therein located to be brought into and out of communication with the cylinder port by relative rotary movement between the valve member and the cylinder bank, the leading and trailing edge portions of said exhaust port being shaped relative to the leading and trailing edge portions, respectively, of the cylinder port to provide for slower opening of the exhaust port as the ports come into communication with each other than closure thereof as the ports pass out of communication with each other.

4. In a bi-rotary engine, a cylinder bank including a cylinder having a port at its outer end, and an annular valve member having an exhaust port therein located to be brought into and out of communication with the cylinder port by relative rotary movement between the valve member and the cylinder bank, said cylinder port being generally symmetrical with respect to the axis of the cylinder and the leading portion of the exhaust port being narrower in lateral direction than the trailing portion thereof.

5. In a bi-rotary engine, a cylinder bank including a cylinder having a port at its outer end, and an annular valve member having an exhaust gas passage extending therethrough, said passage terminating at its inner end in an exhaust port located to be brought into and out of communication with the cylinder port by the relative rotary movement between the valve member and the cylinder bank and the leading and trailing portions of the wall of said exhaust passage being shaped to direct the outflowing gases after they leave the cylinder port in a direction having a tangential component in the direction of relative movement of the valve member with respect to the cylinder bank.

6. In a bi-rotary engine, a cylinder bank including a cylinder having a passage terminating at its outer end in a cylinder port, an annular valve member having an exhaust port and an inlet port therein adapted to be brought into communication with the cylinder port in the order named by relative rotary movement between the valve member and the cylinder bank, said exhaust port and said inlet port being located to be in overlapping communication with the cylinder port and the inlet being shaped to direct a high velocity stream of inflowing gas in a direction tending to confine it to the leading portion of the cylinder port passage during the period of overlapping communication of the ports.

7. In a bi-rotary engine, a cylinder bank including a cylinder having a passage terminating at its outer end in a cylinder port, and an annular valve member having an exhaust passage and an inlet passage therein each terminating in a valve port, said valve ports being located to bring said passages into communication with the cylinder port in the order named by relative rotary movement between the valve member and the cylinder bank, the spacing between said inlet and exhaust ports being such that overlapping communication is established with the cylinder port and the leading portion of the wall of said inlet passage being formed to direct the inflowing gas in a direction tending to confine it to the leading portion of said cylinder passage during the period of overlapping communication between said ports.

8. In a bi-rotary engine, a cylinder bank including a cylinder having a cylinder port at its outer end, and an annular valve member having an exhaust passage and an inlet passage therein each terminating in a valve port, said valve ports being located to bring said passages into communication with the cylinder port in the order named by relative rotary movement between the valve member and the cylinder bank, the spacing between said inlet and exhaust ports being such that overlapping communication is established with the cylinder port, and the leading portion of the wall of said inlet passage being formed to direct the inflowing gas into the cylinder port in a direction having a tangential component in the direction of relative rotation of the cylinder bank with respect to the valve member.

9. In a bi-rotary engine, a cylinder bank including a cylinder having a cylinder port at its outer end, and an annular valve member having an exhaust passage and an inlet passage therein each terminating in a valve port, said valve ports being located to bring said passages into communication with the cylinder port in the order named by relative rotary movement between the valve member and the cylinder bank, the spacing between said inlet and exhaust ports being such that overlapping communication is established with the cylinder port and the leading portion of said inlet passage adjacent to the inlet port being shaped to accelerate the velocity of the gas flowing into the cylinder when the cylinder port first communicates with the inlet.

10. In a bi-rotary engine, a cylinder bank including a cylinder having a port at its outer end, and an annular valve member having an exhaust port and a main inlet port located to be brought into communication with the main cylinder port in the order named by relative rotary movement between the cylinder bank and the valve member and an auxiliary inlet port located between said exhaust port and said main inlet port.

11. In a bi-rotary engine, a cylinder bank including a cylinder having a port at its outer end, and an annular valve member having an exhaust port and a main inlet port located to be brought into communication with the cylinder port in the order named by relative rotary movement between the valve member and the cylinder bank, and an auxiliary inlet port located between said exhaust port and said main inlet port, said auxiliary port being spaced from the exhaust port to provide overlapping communication between the cylinder port on the one hand and the exhaust port and said auxiliary port on the other hand.

12. In a bi-rotary engine, a cylinder bank including a cylinder having a port at its outer end, an annular valve member having an exhaust port and a main inlet port located to be brought into communication with the cylinder port in the order named by relative rotary movement between the valve member and the cylinder bank and an auxiliary inlet port located between said exhaust port and said main inlet port, said auxiliary port having a cross-sectional area substantially less than the cross-sectional area of the main inlet port.

13. In a bi-rotary engine, a cylinder bank including a cylinder having a port at its outer end, an annular valve member having an exhaust port and a main inlet port located to be brought into communication with the main cylinder port in

the order named by the relative rotary movement between the valve member and the cylinder bank and an auxiliary inlet port located between said exhaust port and said main inlet port, said auxiliary port and the portion of the inlet passage adjacent thereto being shaped to direct inflowing gas with accelerated velocity into the cylinder port.

14. In a bi-rotary engine, a cylinder bank including a cylinder having a port at its outer end, an annular valve member having an inlet passage therethrough and a baffle bridging said passage adjacent to the inner end thereof to provide an auxiliary inlet port and a main inlet port located to be brought into communication with the cylinder port in the order named by relative rotary movement between the valve member and the cylinder bank.

15. In a bi-rotary engine, a cylinder bank including a cylinder having a port at its outer end, an annular valve member having an inlet passage extending therethrough and a baffle located in said passage to provide an auxiliary inlet port and a main inlet port located to be brought into communication in the order named by relative rotary movement between the valve member and the cylinder bank, said baffle and the leading portion of the wall of the inlet passage being shaped to provide an auxiliary inlet port opening the lateral extent of which is several times the length of the opening in the plane of rotation.

16. In a bi-rotary engine, a cylinder bank including a cylinder having a passage terminating at its outer end in a port, an annular valve member having an inlet passage extending therethrough and a baffle in said passage providing an auxiliary inlet port and a main inlet port arranged to be brought into communication with the cylinder port in the order named by relative rotary movement between the valve member and the cylinder bank, the leading portions of the edges of said auxiliary inlet port and of said main inlet port being shaped to register with the leading portion of the edge of the cylinder port as the respective valve ports come into communication with the cylinder port.

17. In a bi-rotary engine, a cylinder bank including a cylinder having a passage terminating at its outer end in a port, an annular valve member having an inlet passage extending therethrough and a baffle in said passage providing an auxiliary inlet port and a main inlet port arranged to be brought into communication with the cylinder port in the order named by relative rotary movement between the valve member and the cylinder bank, the leading portion of the edge of said auxiliary port being shaped to register with the leading portion of the edge of the cylinder port as the ports come into communication and the trailing portion of the edge of the main inlet port being shaped to register with the trailing portion of the edge of the cylinder port as the ports move out of communication.

18. In a bi-rotary engine, a cylinder bank including a cylinder having a cylindrical passage at its outer end terminating in a cylindrical port,

an annular valve member having an exhaust port, an auxiliary inlet port, and a main inlet port located to be brought into communication with the cylinder port in the order named by relative rotary movement between the valve member and the cylinder bank, said auxiliary inlet port being arcuate in form and arranged to register with the leading portion of the cylinder port as these ports come into communication and further being located with respect to the exhaust port so that the exhaust port and the auxiliary inlet port are in overlapping communication with the cylinder port, and the trailing portion of the edge of the exhaust port being shaped to register with the trailing portion of the edge of the cylinder port as communication between the two latter ports is closed.

19. In a bi-rotary engine, a cylinder bank including a cylinder having a circular port at its outer end, and an annular valve member having an exhaust gas passage extending therethrough, said passage terminating at its inner end in an exhaust port located to be brought into and out of communication with the cylinder port by the relative rotary movement between the valve member and the cylinder bank, the leading and trailing edge portions of said exhaust port being substantially parallel to each other, and curved to substantially the same radius of curvature as said circular cylinder port, and the direction of curvature of said trailing edge portion being such that the trailing edge portion substantially registers with the trailing edge portion of the cylinder port as the ports pass out of communication with each other.

20. In a bi-rotary engine, a cylinder bank including a cylinder having a port at its outer end, and an annular valve member having an exhaust gas passage extending therethrough, said passage terminating at its inner end in an exhaust port located to be brought into and out of communication with the cylinder port by the relative rotary movement between the valve member and the cylinder bank, the leading and trailing portions of the wall of said exhaust passage being curved in the plane of rotation, and the direction of curvature thereof being such as to direct the outflowing gases after they leave the cylinder port in a direction having a tangential component in the direction of relative movement of the valve member with respect to the cylinder bank.

21. In a bi-rotary engine, a cylinder bank including a cylinder having a port at its outer end, an annular valve member providing an auxiliary inlet port and a main inlet port located to be brought into communication with the cylinder port in the order named by relative rotary movement between the valve member and the cylinder bank, there being an inlet passage formed in said valve member communicating with said auxiliary inlet port, and the walls of said passage converging in the direction of flow of the gases through the passage to accelerate the flow thereof and increase the velocity of delivery thereof from said auxiliary inlet port.

ANDRÉ J. MEYER. 65
